UNITED STATES PATENT OFFICE.

SAMUEL G. WELLS, OF CHICAGO, ILLINOIS.

SWITCH LOCK.

1,406,790.

Specification of Letters Patent. Patented Feb. 14, 1922.

Application filed December 29, 1919. Serial No. 348,129.

To all whom it may concern:

Be it known that I, SAMUEL G. WELLS, a citizen of the United States, and a resident of the city of Chicago, county of Cook, and 5 State of Illinois, have invented certain new and useful Improvements in Switch Locks, of which the following is a specification.

My invention relates to new and useful improvements in switch locks, and has for 10 its object the provision in a switch lock of means for latching and locking the switch lever in position.

Another object is the provision in a switch lock of means for retaining the switch lever 15 in latched position after the same has been unlocked.

Other objects will appear hereinafter.

The invention consists in the combinations and arrangements of parts hereinafter 20 described and claimed.

The invention will be best understood by reference to the accompanying drawings forming a part of this specification, and in which,

25 Fig. 1 is a side elevational view of my invention with a portion of the housing removed,

Fig. 2 is a sectional view taken on substantially line 2—2 of Fig. 1, and

30 Fig. 3 is a fragmentary side elevational view of my invention, showing the lever in locked and latched position.

The approved form of construction, as 35 illustrated in the drawings comprises a base 6, upon which is mounted, and preferably made integral therewith, a standard 7, upon which is mounted, and preferably made integral therewith, a guide post 32, thereby forming in the member 7 a slot 8. The central portion of the member 7 is reduced and the upper end 9 is enlarged for a purpose to be described hereinafter. Secured to the base 6 adjacent one side of the member 7 and centrally thereof is a standard 10, the upper

45 end of which is reduced, as shown in Fig. 2 to form a guide member 11. Extending between the member 11 and the standard 7 is a rivet 12 by which two members 13 and 14 are pivotally mounted in position. The

50 member 13 is provided with a tail piece 15, and an arm 16 at its upper end extending across the slot 8 in position to be engaged by the switch-operating lever 31 as such lever is moved downwardly into the slot 8. The

55 member 13 is also provided with an ear 17 providing a shoulder at the upper end of the

member. As shown, the member 14 is reduced at its upper end portion 18 and is comparatively very heavy at its depending arm portion 19 for returning the member 18 to normal upright position upon being released after displacement. Pivotedly mounted at 20 upon the portion 9 of the member 7 is a locking arm 21 provided at its end 22 with a notch 24 in which the end 18 of the member 14 is adapted to engage, a downwardly extending lug 23 serving to limit the movement of the member 18 toward the right in Fig. 1.

The device is intended for locking the lever and switch in position, so that when the switch is either opened or closed, the same may not be removed to another position without releasing the switch lever 31 from engagement in the groove 8. When the device is in operative position so as to receive the switch lever 31, the various parts are in the position shown in Fig. 1. Upon the lever 31 striking the member 16, the member 13 is moved upon the pivot 12, so that the ear 17 passes beneath the curved end 22 of the locking arm 21. As the lever 31 proceeds downwardly it engages the edge of the member 14 for swinging such member in counter-clockwise direction in Fig. 1. Upon this movement of the member 14, the end 18 disengages from the member 21 and allows the same to fall into engagement with the curved portion of the member 13 at the right of the ear 17 as seen in Fig. 1. When the lever 31 in its downward movement into the slot 8 clears the member 16, the member 13 again swings on its pivot, bringing the ear 17 back of the turned end of the member 21 into the position shown in Fig. 3, in which position of the parts the member 13 is held against swinging, serving thus to lock the lever 31 in the slot 8.

Mounted upon the portion 9 of the member 7 is a housing 27 which is adapted to enclose the arm 21 and the ear 17 of the member 13 so that these parts cannot be reached from the outside of the housing. Mounted upon the member 9 and projecting through the housing 27 is a barrel 28, the end of which is provided with a slot 26, in which a key may be inserted. The interior of the barrel 28 may be provided with suitable tumblers so that a specially designed key will be necessary to operate the device. Upon inserting the key into the barrel 28 and turning the portion in which the slot 26

appears, a tongue 29 is brought into engagement with the under surface of the member 21 and causes the same to be raised, as shown in dotted lines in Fig. 3. With the 5 arm 21 raised in this manner, the member 13 still serves effectively as a latch for preventing upward movement of the switch lever 31. As will be appreciated, when it is desired to move the lever 31 upwardly out of 10 the slot 8, it is necessary first to swing the arm 16 toward the right in said Fig. 3, this being accomplished readily by an upward pull on the tail piece 15.

My device is designed to be bolted to the 15 cross ties of a track and the base 6 may be formed large enough to allow for a firm mounting of the device adjacent the rail.

In order to prevent the member 13 from moving downwardly too great a distance so 20 as to move the member 16 out of the path of the lever 31, a stop block 30 is mounted upon the member 13 in position to engage the standard 7. Also, as shown in Fig. 3, the 25 guide post 32 is formed with the upper end 33 curved or beveled to permit a ready reception of the member 31 into the slot 8.

While I have illustrated and described the preferred form of construction for carrying 30 my invention into effect, this is capable of variation and modification without departing from the spirit of the invention. I, therefore, do not wish to be limited to the precise details of the construction set forth, but desire to avail myself of such variations 35 and modifications as come within the scope of the appended claims.

Having described my invention, what I 40 claim as new and desire to secure by Letters Patent is:

40 1. A switch lock comprising a supporting member; a guide member mounted adjacent to and spaced from said supporting member; a latch pivotally mounted on said supporting member; a locking member adapted, 45 when in operative position, to engage said latch; and means projecting into the space separating said supporting member and said guide member for retaining said locking member in in-operative position, substantially as described.

50 2. A switch lock comprising a supporting member; a guide member mounted adjacent to and spaced from said supporting member; forming a passage between said supporting member and said guide member; a latch pivotally mounted on said member, one end of said latch projecting into said passage; a locking member pivotally mounted on said supporting member and adapted in 55 one position for locking said latch in said projecting position; and a member for retaining said locking member in in-operative position, one end of said member projecting into said passage, substantially as described.

60 3. A switch lock comprising a supporting

member; a guide member mounted adjacent to and spaced from said supporting member, forming a passage between said supporting member and said guide member; a latch pivotally mounted on said supporting member, one end of said latch projecting into said passage; a locking member pivotally mounted on said supporting member and adapted in one position for locking said latch in said projecting position; and a member pivotally mounted on said supporting member for retaining said locking member in in-operative position, one end of said last mentioned member being normally held by gravity projecting into said passage, substantially as described.

4. A switch lock comprising a supporting member; a vertically extending guide member mounted adjacent to and spaced from said supporting member, provided with a passage between said supporting member and said guide member; means mounted on said supporting member for latching a switch lever in said passage; locking means in the form of a latch for holding said first named latching means in retaining position, means operable by a key for releasing said locking means, and automatically acting means for holding said locking means releasably out of operative position, substantially as described.

5. A device of the class described, comprising a standard provided with an upwardly opening notch adapted to receive a lever therein; a pivoted latch weighted at one side for holding it normally in position above said notch, being adapted to be displaced downwardly for permitting the lever to pass; a stop on the weighted end of said latch for preventing upward movement of the latch from its normal position away from said notch, whereby the latch serves to hold the lever against withdrawal; an ear on said latch; and a gravity operable latch engaging said ear for locking said latch against downward movement, substantially as described.

6. A device of the class described, comprising a standard provided with an upwardly opening notch adapted to receive a lever therein; a latch extending normally into position above said notch and adapted to be displaced downwardly for permitting the lever to pass; means for preventing upward movement of said latch from its normal position away from said notch whereby the latch serves to hold the lever against withdrawal; and a pivoted latch operable by gravity for holding said first named latch against downward movement toward the notch, substantially as described.

7. A device of the class described, comprising a standard provided with an upwardly opening notch adapted to receive a lever therein; a latch extending normally

into position above said notch and adapted to be displaced downwardly for permitting the lever to pass; means for preventing upward movement of said latch from its normal position away from said notch whereby the latch serves to hold the lever against withdrawal; a second pivoted latch operable by gravity adapted by engagement with said first named latch to hold said first named latch against downward movement toward the notch; and means adjacent said first named latch for holding releasably said second latch out of operative engagement with said first named latch, substantially as described.

8. A device of the class described, comprising a standard provided with an upwardly opening notch, a movable member adapted to engage said notch; a latch extending normally into position above said notch and adapted to be displaced downwardly for permitting the movable member to pass; means for preventing upward movement of said latch from its normal position away from said notch whereby the latch serves to hold the lever against withdrawal; a second latch adapted by engagement with said first named latch to hold said first named latch against downward movement toward said notch; releasable means for holding said second latch out of operative engagement with said first named latch; and means actuated by the movement of said movable member into said notch for throwing said releasable means out of operation for permitting said second latch to engage said first named latch, substantially as described.

9. A device of the class described, comprising a standard provided with an upwardly opening notch adapted to receive a lever therein; a latch extending normally into position above said notch and adapted to be displaced downwardly for permitting the lever to pass; means for preventing upward movement of said latch from its normal position away from said notch whereby the latch serves to hold the lever against withdrawal; a second pivoted latch operable by gravity adapted by engagement with said first named latch to hold said first named latch against downward movement toward said notch; a pivotally mounted member adapted in one position to hold said second latch out of operative engagement with said first named latch; and means adapted normally to hold said pivotally mounted member in position for supporting said second latch out of operative position, substantially as described.

10. A device of the class described, comprising a standard provided with an upwardly opening notch adapted to receive a lever therein; a latch extending normally into position above said notch and adapted

to be displaced downwardly for permitting the lever to pass; means for preventing upward movement of said latch from its normal position away from said notch whereby the latch serves to hold the lever against withdrawal; a second pivoted latch operable by gravity adapted by engagement with said first named latch to hold said first named latch against downward movement toward said notch; a pivotally mounted member adapted in one position to hold said second latch out of operative engagement with said first named latch; and a depending arm adapted by gravity to hold said pivotally mounted member yieldingly in position for supporting said second latch out of operative position, substantially as described.

11. A device of the class described, comprising a standard provided with an upwardly opening notch; a movable member adapted to engage said notch; a latch extending normally into position above said notch and adapted to be displaced downwardly for permitting the lever to pass; means for preventing upward movement of said latch from its normal position away from said notch whereby the latch serves to hold the lever against withdrawal; a second latch adapted by engagement with said first named latch to hold said first named latch against downward movement toward said notch; a pivotally mounted member adapted in one position to hold said second latch out of operative engagement with said first named latch; and means adapted normally to hold said pivotally mounted member in position for supporting said second latch out of operative position and actuated by the movement of the movable member into said notch for throwing said pivotally mounted means out of operation for permitting said second latch to engage said first named latch, substantially as described.

12. A device of the class described, comprising a standard provided with an upwardly opening notch adapted to receive a lever therein; a latch extending normally into position above said notch and adapted to be displaced downwardly for permitting the lever to pass; means for preventing upward movement of said latch from its normal position away from said notch whereby the latch serves to hold the lever against withdrawal; a second latch adapted by engagement with said first named latch to hold said first named latch against downward movement toward said notch; a pivotally mounted member adapted in one position to hold said second latch out of operative engagement with said first named latch; and a depending arm adapted by gravity to hold said pivotally mounted member in position for supporting said second latch out of operative position and adapted by engagement with said lever in its movement into said

notch to throw said pivotally mounted member out of operation for permitting said second latch to engage said first named latch, substantially as described.

5 13. A device of the class described, comprising a standard provided with an upwardly opening notch; a movable member adapted to engage said notch; a latch extending normally into position above said notch and adapted to be displaced downwardly for permitting the lever to pass; means for preventing upward movement of said latch from its normal position away from said notch whereby the latch serves 10 to hold the lever against withdrawal; a second latch adapted by engagement with said first named latch to hold said first named latch against downward movement toward said notch; a pivotally mounted member 15 adapted in one position to hold said second

latch out of operative engagement with said first named latch; a depending arm adapted by gravity to hold said pivotally mounted member in position for supporting said second latch out of operative position and 25 adapted by engagement with said movable member in its movement into said notch to throw said pivotally mounted member out of operation for permitting said second latch to engage said first named latch; and a housing surrounding the operative parts of the device for preventing unauthorized operation thereof, substantially as described. 30

In testimony whereof I have signed my name to this specification in the presence of 35 two subscribing witnesses.

SAMUEL G. WELLS.
